Patented Aug. 15, 1916.

UNITED STATES PATENT OFFICE.

GUSSIE A. LEE, OF OMAHA, NEBRASKA, ASSIGNOR OF ONE-HALF TO ERIC T. JOHNSON,
OF OMAHA, NEBRASKA.

OIL-BURNER.

1,194,519.

Specification of Letters Patent. Patented Aug. 15, 1916.

Application filed February 13, 1915. Serial No. 7,994.

To all whom it may concern:

Be it known that I, GUSSIE A. LEE, a citizen of the United States, residing at Omaha, in the county of Douglas and the State of Nebraska, have invented a new and useful Improvement in Oil-Burners, of which the following is a specification.

This invention relates to an oil burner adapted to be fitted into stoves or furnaces, and the invention relates especially to the manner of feeding the oil to the burner and admitting air thereto.

The invention consists in the novel features of construction hereinafter described, pointed out in the claim and shown in the accompanying drawings, in which:

Figure 1 is a vertical sectional view, the burner being shown in position. Fig. 2 is a section on the line 2—2 of Fig. 1. Fig. 3 is a section on the line 3—3 of Fig. 1.

In the drawings 1 designates a stove or furnace having the usual pipe 2 for carrying off the products of combustion, and a clean out or draft door 3.

For the usual grate I substitute a horizontal partition 4 which supports a drip pan 5. The two might be integral but it is more convenient to construct the partition and pan separately as shown. The pan has a central sleeve which opens downwardly through the bottom of the pan, and registers with a suitable opening in the partition 4, and opens upwardly beneath a burner cap 7. The cap has inwardly and downwardly extending spaced lugs 8, suitably notched to engage the top of the sleeve 6. By means of this construction the burner is detachably held supported above the

sleeve. Air pipes 9 are arranged in the form of an arch over the burner, discharging downwardly on the same through a common discharge opening 10, and communicating at their lower ends with the space below the partition.

Running into one side of the arch, that is through one of the pipes 9 forming it, is an oil supply pipe 11, which leads to a discharge nozzle 12 arranged in the center of the arch and discharging downwardly through the opening 10. The pipe 11 is provided with a suitable valve 13. The oil drops upon the burner cap 7 and air is fed upwardly through the sleeve 6 and around the cap and also discharged downwardly through the opening 10, the air supply being drawn from the lower portion of the stove. The oil supply is regulated by the valve 13, and the air and draft by means of the door 3 and the usual slide 3^a carried thereby. The sleeve 6 forms a centrally arranged air tube.

What I claim is:

In an oil burner, a drip pan, an air tube centrally carried by the pan and opening downwardly through the bottom of the pan, a semi-spherical burner cap supported on the upper end of said tube and partially enclosing the same, the tube opening upwardly beneath said cap, an oil supply pipe adapted to discharge vertically upon the top of the cap, and an air supply pipe within which said oil pipe is arranged.

GUSSIE A. LEE.
